(57) **CLAIM**

The ornamental design for a holding strap for wireless ear-bud style earpieces clip, as shown and described.

DESCRIPTION

FIG. 1 is a front perspective view of a holding strap for wireless ear-bud style earpieces, showing my new design; FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a right side elevational view thereof with stems of the wireless ear-bud style earpieces separated from the holding strap; and,

FIG. 10 is a right side elevational view thereof with the stems of the wireless ear-bud style earpieces received in the holding strap.

The broken lines shown in the drawings depict portions of the holding strap for ear-bud style earpieces clip that form no part of the claim.

The broken line showing the earpieces in FIGS. 9 and 10 depicts environment and forms no part of the claimed design.

1 Claim, 10 Drawing Sheets
